CLAIM

The ornamental design for an airbrush, as shown and described.

DESCRIPTION

FIG. 1 is a front, right and top perspective view of an airbrush, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of the portion labeled 9 in FIG. 2.

The broken lines shown in the drawings illustrate portions of the airbrush that form no part of the claimed design.

The dot-dash broken lines surrounding details shown in FIGS. 2 and 9 are for the purpose of annotating the enlarged views only and form no part of the claimed design.
